UNITED STATES PATENT OFFICE.

JOHN D. KING, OF SYRACUSE, NEW YORK.

CHAIN-LINK COUPLING.

1,426,877.

Specification of Letters Patent. Patented Aug. 22, 1922.

Application filed March 4, 1922. Serial No. 540,991.

To all whom it may concern:

Be it known that I, JOHN D. KING, a citizen of the United States, of Syracuse, in the county of Onondaga, in the State of New York, have invented new and useful Improvements in a Chain-Link Coupling, of which the following, taken in connection with the accompanying drawings, is a full, clear, and exact description.

10 This invention relates to a chain link coupling for replacing broken links, extending or shortening a chain and for any other emergency in which a link coupling of this character might be useful, the main object 15 being to provide a link coupling of this character which can be easily and quickly attached to or detached from separate chains or links to connect or disconnect the same and thus permit the coupled sections to be 20 used for any purpose to which a chain of uniform links might be applied.

Other objects and uses relating to specific parts of the coupling will be brought out in the following description:

25 In the drawings:

Figures 1 and 2 are face views of the link taken at right angles to each other.

Figure 3 is an end view of the same link.

As illustrated, this link consists of a 30 round metallic rod or wire bent intermediate its ends to form a return bend —1— and opposite arms —2— and —3—, one of which as —2— terminates in an eye —4— bent from the main body toward and in the 35 same general direction as the bend —1— in longitudinally spaced relation thereto to leave ample space for the free play of the adjacent chain link —a— interlocked with the bend or loop —1—, the intermediate portion of the arm —2— being also bent inwardly toward the terminal end of the eye —4—.

The arm —2— and its eye —4— are disposed in a substantially flat plane at right 45 angles to the axis of the eye, while the other arm —3— is somewhat longer than the arm —2— and is extended forwardly some distance to one side of the plane of the eye —4— and also some distance beyond the 50 outer edge of the eye where it is formed with a return bend —5— terminating in an extension —6— which is offset at substantially right angles to the adjacent portion of the bend —3— in the direction of extension of 55 and in substantially the same plane as the eye —4— but in spaced relation thereto to

form a passage —7— of sufficient size to permit one side of any one of the links as —a— to pass therethrough.

That is, the arm —2— is disposed at one 60 side of the axis —4—, while the arm —3— is disposed at the opposite side of said axis but in axially spaced relation to the eye a sufficient distance to allow one side of any 65 of the links to pass through the intervening space, said arm —3— being disposed a distance from the axis of the eye substantially equal to that of the corresponding side of the eye, while its forward end is bent at —5— downwardly and laterally to the plane 70 of the eye in which the extension —6— is located.

The lower end of the extension —6— at its junction with the arm —3— projects below a straight line passing through the axes 75 of the eye —4— and return bend —1— a distance nearly equal to the radius of said eye, while the other end of the extension projects a similar distance to the opposite side of said straight line, thus permitting one 80 of the links as —a— to lie in the plane of said straight line when engaged with the eye —4— and embracing the extension —6—, which latter is spaced apart from the eye 85 a distance considerably less than one of the links —a— to allow it to enter the adjacent link when interlocked with the eye —4— and next adjacent link.

This extension —6— is substantially flat in the plane of the eye —4— and gradually 90 increases in width lengthwise of the coupling toward its free end so that when inserted in the link —a—, which is interlocked with the eye —4—, it will slightly overhang the adjacent end of the next adjacent 95 link —a— to prevent accidental displacement of the extension from the link through which it extends when the chain is tightened as shown more clearly in Figure 2.

After the link —1— is interlocked with 100 the eye —4— while the latter is opened, said eye may be closed by bending its free end toward the arm —2— as shown by dotted lines in Figure 2 to retain the link in operative connection therewith, thereby 105 fastening the coupling link to one section of the chain.

In order to attach the coupling to the other section of the same shown at the right of Figures 1 and 2, the extension —6— may 110 be slipped through the attaching link and the latter drawn along the arm —3— until

engaged with the return bend —1—, whereupon the extension —6— may be brought upwardly from the lower side through the opening in the link which is attached to 5 the eye —4—, thereby allowing one side of the last named link to rest on the arm —3— near its junction with the extension —6— whereby the two chain sections will be connected together by the coupling, the reverse operation being necessary to separate 10 the chain sections.

What I claim is:

1. An emergency link-coupling for chains consisting of a rod or wire bent intermediate its ends to form a return bend-loop and opposite arms extending in the same general direction from the loop, one of the arms terminating in an eye and the other arm extending some distance beyond the 15 eye and terminating in an offset extension in a plane substantially parallel with the eye.
2. An emergency link-coupling for chains consisting of a rod or wire bent intermediate its ends to form a return bend-loop and opposite arms extending in the same general direction from the loop, one of the arms terminating in an eye and the other arm extending some distance beyond the eye and 20 terminating in an offset extension in a plane

substantially parallel with the eye, said extension being disposed in substantially the same plane as that of the eye and extended to opposite sides of a straight line drawn through the axes of the eye and loop. 35

3. A coupling-link for chains consisting of a rod or wire bent intermediate its ends to form a return bend-loop and opposite arms extending in the same general direction from opposite sides of the loop, one 40 of the arms terminating in an eye extending toward the other arm and toward the loop, the other arm being extended some distance beyond the eye in transversely spaced relation thereto to form an intervening passage for one of the links of the chain to be coupled and terminating in an offset extension disposed in substantially the same plane as that of the eye and across a direct line extending through the axis of the loop 45 and eye, said extension being substantially flat in the direction of extension of the axis of the eye and gradually increasing in width toward its free end.

In witness whereof, I have hereunto set 55 my hand this 27th day of February, 1922.

JOHN D. KING.
